Primary Examiner — Kevin K Rudzinski(74) *Attorney, Agent, or Firm* — ScienBiziP, P.C.(57) **CLAIM**

The ornamental design for a wearable blanket, as shown and described.

DESCRIPTION

FIG. 1 is a front, right, and top perspective view of a wearable blanket, wherein covers of the wearable blanket are expanded, showing my design.

FIG. 2 is a rear, left, and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.
